UNITED STATES PATENT OFFICE.

ISRAEL KORETZKY, OF NEW YORK, N. Y., ASSIGNOR TO LEWIS J. MORRISON, OF
NEW YORK, N. Y.

PORTABLE ELECTRIC LIGHT.

1,146,628.

Specification of Letters Patent. Patented July 13, 1915.

Application filed June 29, 1914. Serial No. 848,006.

To all whom it may concern:

Be it known that I, ISRAEL KORETZKY, a subject of the Czar of Russia, residing at New York, in the county of New York and 5 State of New York, have invented certain new and useful Improvements in Portable Electric Lights, of which the following is a specification.

My invention relates to portable electric 10 lights, and particularly those of small dimensions and convenient shape for carrying in the pocket and for carrying about in the hand when in use, said lights commonly being known as flash lights. In devices of this character the battery is separable from the casing which carries the lamp, and has exposed contacts which make connection with the lamp terminals, one of these connections being permanently maintained 15 while the battery is in the casing and the other connection a manually operable circuit-closer which makes connection with an exposed terminal of the battery. The push buttons and other circuit-closers commonly 20 employed are only adapted for temporarily closing the circuit so that the light can be used for only a short period and will immediately go out as soon as the push button or other device is released. Other difficulties that are experienced with the ordinary type of circuit closer mentioned are, 25 that the actual effecting of a contact at the desired moment is uncertain, the contact is liable to accidentally become closed and 30 remain closed, without the knowledge of the user, thereby exhausting the battery, and also some of these circuit-closers are so delicately constructed as to become impaired at the slightest provocation.

40 My invention provides a portable electric light of the type mentioned which has embodied therein a simple, yet effective circuit-closer which is absolutely positive in its operation, easy to manipulate and is 45 adapted to be positioned so that the circuit will remain closed if it is so desired, thereby enabling one to use the light for an extended period of time without continually maintaining pressure on the button or other 50 means for operating the circuit closer.

Referring to the drawings annexed hereto and forming a part of this specification, and in which I have illustrated the preferred embodiment of my invention: Figure 55 1 is a longitudinal section and circuit-closer,

the circuit-closer being in the open position. Fig. 2 is a front elevation view partly in section showing the circuit-closer in the closed position. Fig. 3 is a view showing the details of the circuit-closer. Fig. 4 is a view similar to that shown in Fig. 2 but showing a modified form of circuit-closer. Fig. 5 shows a modified form of spring contact device.

Referring to the drawings: The casing 65 1 is provided at the top thereof with a threaded socket 2 adapted to receive and retain in place the usual type of incandescent electric light bulb 3, while the bottom of the said casing 1 is provided with a hinge latch 70 door 4 which is adapted to retain the battery 5 in place within the casing when the said door 4 is closed. The battery 5 is of the usual type having the exposed terminals 6 and 7 the former being adapted to 75 form a permanent contact with the terminal 8 on the bulb, and the latter being adapted to be engaged by the circuit-closer to light the lamp bulb.

The circuit-closer 9 is disposed as is usual 80 in the end of the casing 1 in a suitable position to engage the exposed terminal 7 of the battery, and is composed of the leaf spring member 10 suitably secured to the casing 1 at 11 by solder or screws. The leaf 85 spring member 10 has disposed at its upper end directly opposite to the said terminal 7, a threaded boss 12 adapted to receive the push button 13 having the threaded shank 14, the end of which is adapted to engage 90 the terminal 7 when the push button 13 is pushed in or when the said button is turned so as to screw the said shank through the said boss into permanent engagement with the terminal 7. Thus it will be evident that 95 when it is only desired to light the light for a short period of time it is only necessary to simply push the button 13 in the usual manner, however if it is desired to use the light for an extended period of time the 100 simple operation of screwing the shank 14 against the terminal 7 serves to keep the light lighted without maintaining constant pressure on the button 13 extending through the opening 15 in the casing 1.

In Fig. 4 I have illustrated a modification of the circuit-closer in that I have provided the shank 14 with a collar 16 which is of larger diameter than the opening 15 in the casing 1 thereby providing against the 110

accidental unscrewing of the said shank 14 completely from the boss 12 in which case it might easily become lost or misplaced.

It is to be understood that I do not limit myself to the specific construction and arrangement of parts herein illustrated and described, but may resort to such modifications as fall within the scope of my claim.

I claim:

- 10 In a portable electric light, a casing containing a battery having contacts, said casing having a push button opening, a spring contact comprising a spring mounted on the inner wall of said casing and having a threaded aperture adjacent the opening in

said casing, a push button having a threaded shank fitting in said aperture and having a knob projecting through said opening, and a collar fixed on said shank between said casing and spring and larger 20 than said push button opening whereby said push button is prevented from being completely unscrewed and removed from said casing, substantially as described.

In testimony whereof I have affixed my 25 signature in the presence of two witnesses.

ISRAEL KORETZKY.
